(57) **CLAIM**

The ornamental design for a water closet, as shown and described.

DESCRIPTION

The file of this patent contains at least one drawing/photograph executed in color. Copies of this patent with color/drawing(s)/photograph(s) will be provided by the Office upon request and payment of the necessary fee.

1.1 is a front perspective view of a water closet showing the new design in a first embodiment;

1.2 is a front perspective view of the water closet in an alternate configuration;

1.3 is a front right perspective view thereof;

1.4 is a right perspective view thereof;

1.5 is a back perspective view thereof;

1.6 is a top perspective view thereof;

1.7 is an enlarged top view of 1.1;

2.1 is a front perspective view of a water closet showing the new design in a second embodiment;

2.2 is a front right perspective view thereof;

2.3 is a right perspective view thereof;

2.4 is a front perspective view of the water closet in an alternate configuration;

2.5 is a front perspective view of 2.1;

2.6 is an enlarged top view of 2.4;

3.1 is a front right perspective view of a water closet showing the new design in a third embodiment;

3.2 is a right perspective view thereof;

3.3 is a front perspective view of the water closet in an alternate configuration;

3.4 is a back perspective view of 3.1; and

3.5 is a front perspective view thereof.

The shadows and light reflections shown in reproductions of the designs are disclaimed; the black diagonal lines shown

(Continued)

on the surface of the product in reproductions 3.1 and 3.2 are disclaimed; the green background shown in reproductions is disclaimed.

The text "Trelino" and logo formed by a semi-circle with two organic shapes angling on top of the semicircle are protected trademarks. Camper Active GmbH is the owner of the aforementioned protected trademarks.
